(57) **CLAIM**

What is claimed the ornamental design for a glove, as shown and described.

DESCRIPTION

FIG. 1 is a perspective view of a glove illustrating the new design with a pocket in a first position;

FIG. 2 is a perspective view thereof with the pocket in a second position;

FIG. 3 is a front elevational view of the new design with the pocket in a first position;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The components of the glove shown in broken lines are for illustrative purposes only and form no part of the claimed design.
